UNITED STATES PATENT OFFICE.

JOHN W. JACKSON, OF NORTH HAVERHILL, NEW HAMPSHIRE.

CAR-COUPING.

SPECIFICATION forming part of Letters Patent No. 339,782, dated April 13, 1886.

Application filed September 24, 1885. Serial No. 177,973. (No model.)

To all whom it may concern:

Be it known that I, JOHN W. JACKSON, a citizen of the United States, residing at North Haverhill, in the county of Grafton and State 5 of New Hampshire, have invented certain new and useful Improvements in Car-Couplings, of which the following is a specification.

My invention relates to improved appliances for supporting and guiding the link and adjusting the coupling-pin of ordinary car-couplings from either side of a car without rendering it necessary for a train-hand to pass in between the cars when connecting the same.

The object of my invention is to provide 15 means whereby this result may be attained without necessitating the removal of the coupling appliances now in common use.

My invention consists in details of construction fully described below, and pointed out in 20 the claims.

In the drawings forming part of this specification, Figure 1 represents the ends of two cars as when approaching and in readiness to couple together automatically. Fig. 2 is an 25 end elevation of a car with its coupling-pin and link-lifter in their normal positon. Fig. 3 is a detached side elevation of one of the wheel-segments. Fig. 4 is a back edge view of the same. Fig. 5 represents one of my 30 improved lifters as when in the proper position to support and guide a link, and Fig. 6 is an elevation of the same as when dropped to its normal position. Fig. 7 is an enlarged 35 side elevation of one of my improved loop-bearings for supporting the lifter, and Fig. 8 is a plan thereof.

The draw-bars A represent those which are at the present time in common use upon freight-cars. These are provided with an 40 ordinary link and pin, respectively B and C. In order to avoid the necessity of guiding the link and adjusting the pin by hand, when it is desired to couple two cars which are approaching each other, I provide a lifter, D, 45 which may be made of a wrought-iron rod bent in the form shown in Figs. 5 and 6. The ends of said lifter-rod may be bent at right angles, as at d, said bent ends serving the purpose of cranks by which the lifter may be operated, 50 or suitable cast-iron cranks, d', as shown in Fig. 1, may be secured thereon, if desired.

In order that the lifter may come in contact with or take hold of a link near its outer end, as seen in one of the cars shown in Fig. 1, and yet not be in danger of being broken or bent 55 when two draw-bars come together, suitable bearings, E, are secured underneath a car at either side and near either end thereof. These are preferably formed of round iron bent in the form of a staple, one end being left longer 60 than the other, and both ends being placed within the mold from which the iron plate-piece E' is cast. This affords a cheap and effective means of connecting the two parts firmly together. The plate E' is provided on 65 either side of the loop E with slots e, through which fastening-bolts G may pass and by which said bearings may be adjustably secured in position. Thus, if the lifter be held up while supporting and guiding a link until 70 it is struck by the draw-bar of an approaching car, it is simply pushed back in the loop-bearings E, by which it is supported near either end, and no damage is done.

Each coupling-pin C is connected by a light 75 chain, H, to a wheel-segment, I, which is mounted upon and rigidly secured to a transverse rod, J, hung in suitable bearings fastened to the end of a car the proper height from the floor thereof. Weighted cranks or levers K 80 are provided at either end of said rod, by which it may be rotated. The chain H rests within the circumferential groove i, formed in the periphery of the wheel-segment I, the circular portion of which is long enough to carry or 85 wind the chain H a limited distance—i. e., to raise a coupling-pin, C, in a draw-bar far enough to clear a link, B, and yet not so far but that its lower end may still remain in the upper part of said draw-bar, this limit in 90 either direction being clearly shown in Fig. 1 of the drawings.

The object of the weighted cranks or levers K at either end of the rod J is to slightly overbalance the weight of the wheel-segment I and 95 coupling-pin C when in the position seen on right-hand car, Fig. 1, the increased weight of said levers J over said parts I and C being simply sufficient to retain said parts in the position last named under ordinary circumstances, but not so great as to prevent a coupling-pin, C, from dropping to its normal posi- 100

tion by the concussion produced by two cars coming together.

The wheel-segment I may be weighted, as seen at i' of the drawings, if desired, and thus 5 save some weight in the levers K.

In order to describe the manner of operating my improved mechanism, let us suppose the left-hand car, Fig. 1, to be standing, and the right-hand car to be in motion. A train-hand has placed his left hand upon the crank d and raised the lifter D in a position to support the link B at the proper elevation. The coupling-pin C of the approaching car is raised to the limit of its upward movement, so the 15 draw-bar of said moving car is in readiness to receive the link on the standing car, and as soon as the two draw-bars come together the said coupling-pin drops to its lower position within the draw-bar. The train-hand or brake- 20 man can then remove his hand from the crank d and the cars are coupled. If the said coupling-pin on the approaching car shall have

been accidentally dropped, the brakeman may with his right hand push the crank K of the approaching car, and thus raise said coupling-pin before the cars come together. 2

Having described my invention, what I claim, and desire to secure by Letters Patent, is—

1. The combination, with the lifter D, having a central bend and a crank, d , of the inclined loop E, permitting the lifter to slide back and supporting the same, the slotted fastening-plate G, and the link B, as set forth. 3

2. The combination, with the coupling-pin C, of the chain H, the segment I, having 3 groove i and weight i' , the rock-shaft J, and weighted cranks K K, as set forth.

In testimony whereof I affix my signature in presence of two witnesses.

JOHN W. JACKSON.
